BASE FOR A FAN

Caryl A. Lindberg, Kirkwood, Mo., assignor to The Emerson Electric Mfg. Company, St. Louis, Mo., a corporation of Missouri

Application February 15, 1954, Serial No. 29,028

Term of patent 14 years

(Cl. D26—7)

To all whom it may concern:

Be it known that the undersigned, Caryl A. Lindberg, a citizen of the United States, residing at Kirkwood, St. Louis County, State of Missouri, has invented a new, original, and ornamental Design for a Base for a Fan, of which the following is a specification, reference being had to the accompanying drawing, forming a part thereof.

Figure 1 is a rear elevation of a base for a fan, showing my new design;

Figure 2 is a front elevational view thereof;

Figure 3 is a top view of the base;

Figure 4 is a side elevation of the base;

Figure 5 is a front elevation of the base; and

Figure 6 is a section on the line 6—6 of Figure 3.

The dotted line showing of a fan in Figures 1 and 2 is for the purposes of illustration only.

What is claimed is:

The ornamental design for a base for a fan, substantially as shown and described.
